UNITED STATES PATENT OFFICE.

GEORGE W. BARNES, OF KENOSHA, WISCONSIN. ASSIGNOR TO SIMMONS COMPANY, OF KENOSHA, WISCONSIN, A CORPORATION OF DELAWARE.

BED-BOTTOM SUPPORT.

Application filed June 20, 1923. Serial No. 646,510.

To all whom it may concern:

Be it known that I, GEORGE W. BARNES, a citizen of the United States, residing at Kenosha, in the county of Kenosha, in the State of Wisconsin, have invented certain new and useful Improvements in Bed-Bottom Supports, of which the following is a specification.

My invention relates to improvements in bed bottom supports, and has particular value in connection with a bed bottom having a substantially rigid underlying base frame for supporting a series of axially vertical spiral springs.

In bed bottoms of the type described, which in the trade, are termed coil springs, in order to distinguish them from wire fabric bed bottoms, a condition is sometimes encountered where the base frame must be extended in width in order to be supported on the side rails of certain bedstead frames. On the other hand, it is desirable to furnish the same bed bottom for use in connection with other types of bedstead frames where the side rails are so shaped and spaced as not to permit the use of said extensions. Hence, said extensions or supports are desirably made or arranged so that they can be slid, swung or folded inwardly, thereby rendering the use of said extensions optional to suit either type of bedstead frame.

The object of my invention is to provide an improved extension of the class described and of the sliding type.

In the drawings which by way of example illustrate my invention as applied to a coil spring of approved design,

Fig. 1 is a fragmentary elevation partly in section showing a corner of a coil spring equipped with my invention,

Fig. 2 is a fragmentary plan view of the principal elements of the device, and

Fig. 3 is a section taken on the line 3—3 of Fig. 1.

Referring to the drawings, 10 represents the side rail of a bedstead frame arranged for use with a coil spring having its support extended. The coil spring base includes a series of the usual slats 11 for supporting the rows of spiral springs 12, the outer row of springs 13 being of lesser height and mounted upon the end portions 14 of said slats 11. Said parts 14 are riveted to the horizontal flange 15 of the side bar

16 of the bed bottom frame and the end of 55 said side bar 16 is riveted to the angle iron end bar 17 as indicated at 18 and 19.

The end bar 17 has an outer depending vertical flange 20 and the end bar 16 has an inner depending vertical flange 21. As 60 shown best in Fig. 3, the end of said side angle bar 16 is cut away so as to provide a space 22 between the vertical flange 20 of the end bar and the end of the vertical flange of the side bar. The sliding extension member 23 comprises a length of metal having a substantially rectangular cross section with its major dimension vertically disposed, said bar being located in the space 22. 65

In order to prevent displacement of the 70 said extension member 23 and also to limit the sliding movement thereof, an extension tongue 24 is provided on the extremity of the side bar flange 21, said extension tongue 24 fitting somewhat loosely in a slot 25 75 punched in the sliding extension piece 23.

When the coil spring is to be used with a type of bedstead frame which will not accommodate the support in its extended position, said support is slid inwardly into the 80 dotted line position shown at 26 in Figs. 1 and 2 so that the end 27 will be substantially flush with the edge of the side bar.

The described details of construction 85 being illustrative of merely one application of my invention, the scope of same should be determined by reference to the appended claims, said claims being construed as broadly as possible consistent with the state 90 of the art.

I claim as my invention:

1. In combination, a bed bottom having a supporting base comprising a border frame which includes a side and an end bar secured together at their ends to form a corner of 95 said frame, and each having a vertically extending flange, a slidable member interposed between the side of the end bar flange and the end of the side bar flange and means for limiting the sliding movement of said member.

2. In combination, a bed bottom having a supporting base comprising a border frame which includes a side and an end bar secured together at their ends to form a corner of 100 said frame, and each having a vertically extending flange, a slidable member interposed between the side of the end bar 105

flange and the end of the side bar flange and means for limiting the sliding movement of said member, and for guiding the sliding movement thereof comprising an extension 5 on said side bar flange.

3. In combination a bed bottom having a supporting base comprising a border frame which includes a side bar and an end bar each of angle iron construction, secured together at their ends to form a corner of said frame, said bars extending substantially at right angles to each other in substantially the same horizontal plane and having vertically extending flanges and a slidable member 10 interposed between the side of the end bar flange and the end of the side bar flange and means for guiding the said bar and limiting the sliding movement thereof comprising-

ing an extension tongue on the end of said side bar flange.

4. In combination, a bed bottom having a supporting base comprising a border frame which includes an angle iron side bar and an angle iron end bar located substantially in the same horizontal plane and extending 25 substantially at right angles to each other, said bars having horizontally disposed flanges lapping each other and united together and having also vertically extending flanges and a slidable slotted member interposed between the side of the end bar flange and the end of the side bar flange, the side bar having an extension tongue thereon cooperating with said slot for guiding said member and limiting its sliding movement.

GEORGE W. BARNES.
